INFANT'S TOILET SEAT MOUNTING MEANS

Ed Bergman, New York, N. Y., assignor to Kiddie Seat Corporation, New York, N. Y., a corporation of New York

Application June 23, 1950, Serial No. 169,961

6 Claims. (Cl. 4—239)

1

The present invention relates to a detachable hinge means for mounting an infant's toilet seat in position to overlie the conventional adult's toilet seat usually found in a household toilet appliance.

As is well known, the bowl of the toilet in the home lavatory or bathroom is provided with an adult seat and a top or cover for the bowl, each of which may be individually raised or lowered to uncover either the seat or the bowl.

It has been customary to mount on such an adult toilet seat, a toilet seat for infants in such manner that it (the infant's seat), may be placed in operative position on the adult toilet seat in which position the top or cover may be lowered to cover the bowl on which the infant's toilet seat may have been swung, or the infant's toilet seat shall be operable so that it can be swung into inoperative position away from the adult toilet seat against the raised top or cover.

Thus, it is desirable that the infant's toilet seat shall at all times be free to be swung clear of the adult toilet seat or onto it in such manner that it will not interfere with the conventional manner in which the household toilet appliance is used and one of the objects of this invention is to provide a mounting means for an infant's toilet seat that is so constructed and arranged that it will serve this purpose.

An example of an infant's toilet seat to which this invention may be applied is illustrated in Pat. No. 1,950,016, granted to S. G. Zuckerman on March 6, 1934.

The present invention contemplates the provision of a fitting or connection which may be mounted under tension on a conventional adult toilet seat in such manner that an infant's toilet seat secured thereon will be operatively positioned to overlie the adult toilet seat in such manner that the operative raising or lowering of the top or cover and the adult toilet seat will not be interfered with.

The present invention contemplates the provision of such an infant toilet seat fitting or mounting means so arranged and constructed that a hinge on which the infant toilet seat may be operatively swung into selected position is provided as an integral part of the said fitting or means.

Other and further objects and advantages of the present invention will be clear from the following description and the drawings appended thereto, in which

Fig. 1 is a side elevation of a toilet seat on which an infant's toilet seat assembly is held in

collapsed overlying position by the detachable hinge means embodying my invention and with the top or cover to the bowl in raised position.

Fig. 2 is a side view of my detachable hinge means to an enlarged scale.

Fig. 3 is a top plan view thereof with the rubber sleeve partially broken away to show the spring control.

Fig. 4 is a rear view thereof, the rubber sleeve broken away and also showing in broken lines the seat element on which the hinge means is mounted.

Referring now to the drawings, the conventional toilet bowl which is not shown since it forms no part of the invention, is provided with the toilet seat 10, illustrated in normal horizontal position on the bowl and on which seat 10 rests the infant's toilet seat assembly 12 in overlying position, an example of which is the infant's toilet seat illustrated in said Pat. No. 1,950,016 and the cover or top 14 of the toilet bowl.

It is understood of course that both the toilet seat 10 and the cover 14 are swingably mounted in the conventional toilet appliance into vertical position, such as that assumed by the cover 14.

In the specification and the claims hereof, I shall refer to the front of my detachable hinge means and the toilet appliance on which it is mounted as that part which is located to the right of Figs. 1, 2 and 3, to the rear thereof as that part which is located to the left of these figures and to the center of my means as that part located at the center of Figs. 3 and 4.

The detachable hinge means generally illustrated in Fig. 2 is secured to the infant seat 16 (see Fig. 2) by means of the Z member 18 which is riveted thereto. Affixed to one, the front or forward one, of the elements of the Z member 18, I provide the adjusting screws 20 and 22 which extend through the slot 24 of the socket plate 26 at the front thereof.

The rear edge of the plate 26 is folded over upon itself to form a sleeve 28 open at both sides, in which sleeve are positioned the ends 30 and 32 continuing inwardly toward the center of my mounting means from the arms 34 and 36 by means of which, as I shall describe, the toilet seat assembly 12 is detachably mounted in position on the toilet appliance.

The ends 30 and 32 with the sleeve 28 form a hinge about which the infant's toilet seat assembly 12 may be selectively swung into raised inoperative position against the top or cover 14 away from the adult toilet seat 10 or together

with the top or cover or as a separate unit swung into horizontal position against the toilet seat 10. The infant's toilet seat also may be swung about this hinge into horizontal operative position as illustrated in Fig. 1.

Each arm 34 and 36 is folded inwardly toward the center of the mounting means to form the pivot ends 30 and 32 which continue as slightly inwardly bent elements 38 and 40 which are pulled together by the spring 42, the ends 44 and 46 of which are looped around the said elements.

The elements 38 and 40 continue outwardly into the arms 34 and 36, which are bent inwardly to form the catch members 48 and 50. The member or tongue 52 which normally extends from the rear of the conventional toilet seat 10 is grasped by the catch members 48 and 50 which are urged against it by the spring 42 to hold in place the infant's toilet seat assembly 12 by my mounting means.

In order to protect the spring 42, I preferably provide the rubber sleeve 54 in which the spring is positioned.

Further, in order to permit readier mounting of my mounting means in the conventional toilet appliance, I preferably form the catch members 48 and 50 of two parts, as illustrated, though it will be understood that a single member unbroken at the ends 30 and 32 thereof may be used, in which case a material sufficiently resilient is required.

It will now be recognized that I have provided a mounting means by which an infant's toilet seat may be detachably secured on any conventional toilet appliance.

This mounting means forms a hinge on which the infant's toilet seat assembly may be selectively swung into vertical inoperative raised position away from the adult toilet seat or into horizontal operative position on the adult toilet seat.

While I have shown and described a certain specific example of my invention, it will be understood that such example is illustrative only and is not given as a limitation, since other modifications within the spirit and scope of the invention will be apparent to those skilled in the art.

Hence, I do not intend to limit myself thereto, but intend to claim my invention as broadly as may be permitted by the state of the prior art and the terms of the appended claims.

I claim:

1. A means for detachably mounting an infant's toilet seat in a conventional toilet appliance, said appliance having a member for receiving the means, an infant's toilet seat, said means comprising a plate secured at one end to the infant's toilet seat, and at the other end formed into a sleeve open at each side, a pair of spaced arms at each side of the means, each arm having an element at one end thereof received in the sleeve, each arm extending down from the element and each arm at the other end thereof turned inwardly to form a catch to be positioned at the side of and below the member in the toilet appliance for receiving the means, each said arm

65

continuing from the said element inward toward the center of the means to form a latch, each arm continuing outward from and downward into the catch, and a resilient means mounted at each end thereof to a latch for urging the arms toward each other.

2. The means of claim 1 and including a second mentioned sleeve for positioning therein the said resilient means.

10 3. The means of claim 1, said elements in the sleeve being spaced from each other.

4. A device for attaching an infant's toilet seat provided with a rearwardly extending tongue to an adult's toilet seat having a rear neck portion, 15 said device comprising a plate means to detachably attach said plate to said tongue, said plate provided at its rear end with a sleeve open at its opposite ends, a pair of separate, similar, symmetrically disposed attaching members having 20 arms extending inwardly into the opposite ends of the sleeve and being rotatable and slideable therein, said attaching members having hooks to engage around and beneath the neck of the adult's toilet seat, and spring means interconnecting 25 said attaching members to draw them toward each other.

5. A device for attaching an infant's toilet seat to an adult's toilet seat comprising an element attachable to the infant's toilet seat and formed 30 with a transverse sleeve at its rear end, a pair of similar, separate, symmetrically disposed attaching members, each made of a single piece of wire and each formed with a first portion slideably and rotatably received in one end of the sleeve, a second portion extending from the first portion at an angle thereto, a third portion extending outwardly from the second portion at an angle thereto, a fourth portion extending downwardly from the third portion at an angle thereto, and a fifth portion extending inwardly from the lower end of the fourth portion substantially parallel to the third portion, said third, fourth and fifth portions of said attaching members constituting means to hookingly engage the adult's seat, a coil tension spring having terminals engaging the second portions of said attaching members.

6. The combination of claim 5 in combination with a flexible tube surrounding the tension spring and disposed between said second portions 50 of said attaching members.

ED BERGMAN.
